UNITED STATES PATENT OFFICE.

MORTIMER CAHILL, OF CHICAGO, ILLINOIS.

THILL-COUPING.

SPECIFICATION forming part of Letters Patent No. 787,661, dated April 18, 1905.

Application filed October 1, 1904. Serial No. 226,741.

To all whom it may concern:

Be it known that I, MORTIMER CAHILL, a citizen of the United States of America, residing at Chicago, in the county of Cook and State 5 of Illinois, have invented certain new and useful Improvements in Thill-Couplings, of which the following is a specification.

My invention relates to certain new and useful improvements in thill-couplings; and 10 its object is to produce a device of this class which shall have certain advantages which will appear more fully and at large in the course of this specification.

To this end my invention consists in certain 15 novel features which are shown in the accompanying drawings and described herein.

In the aforesaid drawings, Figure 1 is a perspective view of my improved thill-coupling, showing the parts assembled. Fig. 2 is a 20 similar view showing the parts in position and illustrating the manner in which the parts are uncoupled, and Fig. 3 is a central longitudinal section through the device.

Referring to the drawings, A is a plate of 25 metal which is adapted to be secured to the lower face of an axle by means of a staple a, (dotted lines, Fig. 1,) carried up over the axle and secured by suitable nuts underneath the plate A. The plate A is bifurcated at its 30 forward end to form two ears a', which are turned back, as illustrated, to form hooks separated substantially the width of a thill-iron B. This thill-iron has laterally-projecting pins b, adapted to lie within the hooks formed by the ears a'. Behind the ears a' is pivoted 35 a block C, bifurcated at its free end, and this block is of such length that when the thill-iron is raised at right angles to the plate A, as seen in Fig. 2, the block can be rotated, 40 its free end swinging just behind the thill-iron. When the block C is swung to the position shown in Fig. 1, the thill-iron can be swung down, as illustrated, the rear end of the thill-iron passing into the furcation at the 45 front end of the block and contacting therewith, so that a fairly tight fit is produced. A block of rubber or other resilient material D is let into a suitable perforation in the block C in front of the pivot, so that when

the thill is down a yielding pressure is exerted upon it, thus preventing rattling. 50

My device is particularly advantageous because of its cheapness, simplicity, and the ease with which the parts can be separated and reassembled. When it is desired to remove the thill-iron from the plate A, the said 55 thill-iron is swung up to the position shown in Fig. 2, when the block C can be rotated about its pivot. The thill-iron can then be moved backward until the pins b are free 60 from the ends of the ears a', and the thill-iron can be lifted out. When the thill-iron is replaced, the reverse operation is performed, and when the block is swung into place, as shown in Fig. 1, its accidental rotation is prevented by engagement with the end 65 of the thill-iron, and the parts cannot be disengaged until the thill-iron is swung up to a position which it could not accidentally occupy. 70

I realize that considerable variation is possible in the details of this construction without departing from the spirit of my invention, and I do not, therefore, intend to limit myself to the specific form herein shown and described. 75

I claim as new and desire to secure by Letters Patent—

1. In a device of the class described, the combination with an axle-plate, bifurcated at 80 its end to form ears, the said ears being turned up and back to form hooks, of a thill-iron having laterally-projecting pins, adapted to lie within said hooks and a bifurcated block pivoted to the axle-plate and arranged to 85 swing up behind said pins when the thill is raised, and to be locked in position by engagement of the end of the thill with the furcation in the block when the thill is lowered.

2. In a device of the class described, the 90 combination with an axle-plate, bifurcated at its end to form ears, the said ears being turned up and back to form hooks, of a thill-iron having laterally-projecting pins, adapted to lie within said hooks, a bifurcated block 95 pivoted to the axle-plate and arranged to swing up behind said pins when the thill is raised and to be locked in position by engage-

ment of the end of the thill with the furcation in the block when the thill is lowered, and a block of resilient material interposed between said block and its pivot to exert a yielding pressure upon the thill-iron.

In witness whereof I have signed the above application for Letters Patent, at Norfolk, in

the county of Madison and State of Nebraska, this 28th day of September, A. D. 1904.

MORTIMER CAHILL.
